Primary Examiner — Susan Bennett Hattan*Assistant Examiner* — Omeed Agilee(74) Attorney, Agent, or Firm — Kenneth H. Jack; Davis & Jack, L.L.C.(57) CLAIM

The ornamental design for a face cradle, as shown.

DESCRIPTION

FIG. 1 is a perspective view of a face cradle showing the new design;

FIG. 2 is a top plan view thereof;

FIG. 3 is a front elevation view thereof; and,

FIG. 4 is a bottom plan view thereof.

A characteristic feature of the article's design is a relatively short arm extension between the face cradle's left and right arm extensions.
